CLOSET OR WARDROBE

Joseph N. Lowe, New York, N. Y.

Application September 1, 1933, Serial No. 687,745

2 Claims. (Cl. 312—144)

This invention relates to closets or wardrobes in the form of a box which has a main body to which ends or closures are applied, such main body at least being preferably composed of corrugated paper board, although other kinds of paper board may be employed, which board is suitably laminated.

An object of the invention is to provide a knock-down box structure which when set up is well adapted for use as a closet or wardrobe adapted to contain articles of clothing or the like, which structure considering the material of which it is preferably composed is very strong and durable in service.

Another object of the invention is to provide such a construction of the box-like structure as that when set up for use it can even be placed in a room of a house or apartment and not be objectionable to the sight, inasmuch as the main body of the structure preferably has an outer finish of hard and tough paper which may, if desired, be ornamented or treated in such way as to appear as if the body is composed of wood with a mahogany, oak or other desired finish; and such box structure being of the knock-down type can be reduced to very small compass so as to take up very little space.

A more specific object of the present invention is to provide a box-like structure wherein the main body is preferably composed of corrugated paper board finished with flat sheets on the outside and inside, and which is creased along lines preferably parallel with the corrugations to provide walls or panels which are foldable together and which may be adjusted to form a box-body rectangular in cross-section and preferably having considerable height when the body is set on end, one of the walls or panels constituting a door; such box body being provided with means at its upper and lower ends for receiving slidable closures, the interengaging means between the closures and the ends of the box body being of such nature that the walls or panels and the closures are all locked together firmly so that a reliably rigid and strong closet or wardrobe is produced which is preferably in the form of a parallelopiped, or the structure may be of cubical or other shape, if desired.

These being among the objects of the present invention, the same consists of certain features of construction and combinations of parts to be hereinafter described and then claimed with reference to the accompanying drawings illustrating a preferred embodiment of the invention and wherein

Fig. 1 is a perspective view of the complete structure showing the door swung open;

Fig. 2 is a plan of the body unit or blank unfolded, the broken lines indicating creases therein;

Fig. 3 is an edge view of the body blank in folded position;

Fig. 4 is an edge view of a slight modification of the body blank wherein the walls or panels are all of the same width;

Fig. 5 is an edge view of the modification in Fig. 4 showing the walls held together by a fastening to facilitate packing or transportation;

Fig. 6 is a section partly broken away of the set-up closet or wardrobe on line 6—6, Fig. 7;

Fig. 7 is a horizontal section on the line 7—7, Fig. 6;

Fig. 8 is an enlarged detail broken section of the upper end of the structure on the line 8—8, Fig. 9;

Fig. 9 is a broken section of the same end on the line 9—9, Fig. 8;

Fig. 10 is an enlarged section of a portion of the structure on line 10—10, Fig. 6;

Fig. 11 is an enlarged section of another portion of the structure on the line 11—11, Fig. 7, showing how a flap on the door fits within the box body;

Fig. 12 is a detail perspective view of one of the slidable closures for the box body;

Fig. 13 is a front elevation of the structure shown in Fig. 1 when closed, and

Fig. 14 is a broken detail section on line 14—14 of Fig. 13.

Referring more particularly to Figs. 2 and 3, the main body of the box-like structure is shown as in the form of a single blank which may be composed of corrugated or other suitable paper board, which is provided with panels 15, 16, 17 and 18 adapted to form the walls of the set-up structure, these panels or walls being defined by creases 19 which extend parallel with each other across the blank, they being formed on the inner surface thereof to create folds 20 so that the blank may be folded as shown in Fig. 3. These creases extend from edge to edge of the blank and one of them defines a relatively narrow flap 21 at the outer edge of the panel or wall 18 which is to constitute a door for the closet or wardrobe.

The box-like body of the closet or wardrobe shown in Fig. 1 wherein the blank has been folded or adjusted so as to form a body rectangular in cross-section, being preferably composed of corrugated paper board, desirably, the corrugations 22 shown in Figs. 8, 9 and 10 extend vertically

cally so as to impart strength in that direction and to support the weight of clothing or the like which may be hung from the top of the closet or wardrobe.

5 In the modification shown in Figs. 4 and 5 the construction is the same as previously described, except that the walls or panels 15a, 16a, 17a and 18a are all the same width, so that when the walls are folded together flat they may be 10 conveniently secured together by the same fastenings which secure the door 18 to the set-up box body.

15 The details of the closet or wardrobe shown in Fig. 1 will now be described with reference to Figs. 6 to 12 inclusive. Rectangular oblong closures 23, 24 are provided for the opposite ends of the box body, each of these being preferably formed of heavy laminated paper board without corrugations. To those surfaces of the closures 20 23, 24 which are to be presented inwardly of the box-body there are secured rectangular frames 25, 25a by means of nails or other fastenings 26. Each of these frames may be composed of wood for obtaining the desired strength and rigidity. 25 Each closure 23, 24 with its attached frame is adapted to be detachably connected with the desired end of the box body.

30 It is preferred that the detachable closures 23, 24 not only seal and close the otherwise open upper and lower ends of the box body, but that they be provided with means whereby they may be slid into the ends along planes transversely of the box body and to at the same time interlock with the box body in such way as to sustain the 35 walls thereof in an enclosing position and to hold the side walls 15, 17 of the box body against separation, thereby to provide a strong and durable closet or wardrobe considering the material of which it is preferably composed. To this end preferably sheet metal slide strips 27, 28 are provided which are of channel formation in cross-section and which are formed with outward edge flanges 29. Slide strips 27, 28 are by means of 40 nails or other suitable fastenings 30 rigidly fastened to the opposite sides of the frame 25 of the closure 23 so that there is a pair of them for such closure, the slide strips extending parallel with the closure along lines underneath the opposite side edges of the closure which project beyond the frame 25, as shown in Fig. 8. Similar slide strips 45 are also secured to the frame 25a of the closure 24 which when the box-like structure is set up constitutes the bottom thereof.

50 As more clearly shown in Figs. 2, 8, 9 and 10, preferably sheet metal guide strips 31, 32 are provided, the guide strips 31 being at the extreme outer ends of the panel or wall 15 and the guide strips 32 being similarly located on the panel or wall 17, these two panels or walls 15, 17 ultimately forming the opposite side walls of the closet or wardrobe when it is set up as in Fig. 1. Each guide strip 31, 32 is formed with outwardly and inwardly turned side flanges 33 at the opposite edges thereof, forming internal grooves which are 55 adapted to receive the flanges 29 of the strips 27, 28. Preferably the guide strips 31, 32 are firmly secured to the walls or panels 15, 17 by means of rivets 34, in such position that they extend in transverse lines across the walls 15, 17 in position to enable the slide strips 27, 28 to be conveniently 60 slid in to the guide strips with a more or less snug fit, yet permitting each closure 23, 24 to be conveniently slid inwardly or outwardly, depending upon whether the box-like structure is to be set-up or knocked down. It will be seen from Fig. 8

65 that when the closures are slid into position, each closure not only seals the end of the box-like body, but at the same time the interlocking strips will sustain all the parts firmly together, and inasmuch as the box-like body is preferably corrugated in a direction vertically thereof, such corrugations will extend transversely of the strips and thereby supplement the action thereof in making the box-like structure rigid, and to produce a closet or wardrobe such as shown in Fig. 10 1, having a front door 18. When the door 18 is being closed its edge flap 21 is guided inwardly along the inner surface of the wall 15, and such flap being defined by a crease 19 at the outer edge of the door has more or less resiliency or outward 15 spring and when the door is closed acts with outward friction against the inner surface of the wall 15 and tends to seal the closet or wardrobe along the corresponding corner thereof.

15 Referring to Figs. 1, 2 and 11 it will be seen 20 that angular notches 35 are formed at the outer ends of the flap 21 where it adjoins the door 18, such notches permitting the flap 21 to be clear of and not hit the closure frames 25, 25a when closing the door. Preferably, for the sake of finish 25 and reinforcement the edges of the door 18 and its flap 21 are provided with a binding or tape 36 which extends along the distance of such edges. Sheet metal protectors 37 are preferably set over the outer corners of the flap 21 and strengthen 30 such corners for obvious reasons.

As shown in Figs. 1, 3 and 4, the wardrobe or cabinet is provided on the wall 15 with a flexible strip 38 which is in the nature of a hasp to engage over a staple 39 which is rigidly secured to the 35 door about mid-way of the length thereof. The staple 39 may receive a pad-lock 40. The wall 15 has flexible strips 41 attached thereto adjacent to its upper and lower ends, and the door 18 and the ends of said strips 41 may be provided 40 with snap fastenings 42 so that by means of these and the pad-lock 40, the door 18 will be so closed from top to bottom and seal the parts together. Hence there will be provided by the present invention a sealed cabinet or wardrobe, which can readily be made moth-proof in any desired way, as there are no exposed open joints.

45 Preferably the frames 25, 25a are of such length in a direction parallel with the guide-strips that when the closet or box is set up the ends of the 50 wall 16 will abut the frames, and also the door 18 will abut them when it is closed, as is clear from Figs. 1 and 7.

If desired, the frame 25 of the top closure 23 may sustain a transverse rail 43 which may be 55 rigidly secured thereto in any desired manner. As the rail 43 is spaced away from the closure 43 it will be seen that the rail is adapted to support hangers for garments and as the improved wardrobe or closet is quite strong any reasonable 60 amount of clothing can be supported from the rail, especially when the upright walls are formed of corrugated paper board with the corrugations extending vertically and also on account of the rigid connection between the closures and the 65 board material.

66 It is obvious that the invention shown and described is susceptible to more or less modification without departing from the scope of the appended claims.

70 What I claim as new is—

75 1. A closet or wardrobe, comprising a rectangular body having stiff walls hinged together along vertical parallel lines, one of the walls serving as a door, and detachable rectangular

serving as a door, and detachable rectangular closures forming the upper and lower ends of the closet at right angles to the parallel hinge connections, each closure having a rectangular reinforcing frame beyond which the edges of the closure slightly project, the opposite side edges of each frame having parallel slides, the opposite walls at right angles to the door having transverse parallel guides for engagement by the slides, whereby at the same time that the ends are provided by the closures the closures hold such opposite walls against separation and produce a self-sustaining closet.

2. A closet or wardrobe, comprising a rectangular body, of paper board creased vertically

to provide stiff walls hinged or foldable together at the creases, one of the walls serving as a door, parallel sheet metal guides secured to and extending transversely of the upper and lower ends of the wall next the door hinge and the wall next the free edge of the door, detachable rectangular closures for the upper and lower ends of the closet, each closure having a rectangular reinforcing frame beyond which the edges of the closure slightly project, and parallel slides secured to opposite edges of each frame for engagement with the guides, the edges of the closures extending over the adjacent edges of the walls.
